COMBINATION BRASSIÈRE SLIP

Rafael Marin, Bronx, N. Y.

Application January 7, 1949, Serial No. 69,693

1 Claim. (Cl. 2—73)

1

This invention relates to new and useful improvements in a combination brassière slip.

More specifically, the invention proposes a combination brassière slip having a brassière top portion provided with an open back and an elastic insert removably mounted across said open back. It is particularly proposed to use slide fasteners for connecting the sides of the insert with the sides of the open back, and to so arrange the slide fasteners that the slides may move downwards to various positions for freeing top portions of the elastic insert in order to release resilient pressure of the brassière against the top portion of the wearer's body.

The dominating feature of the new brassière slip resides in the fact that when the elastic insert is in position and the slide fasteners are closed the brassière top portion of the garment is completely operative for effectively supporting the bust. When the wearer desires to relax and does not require complete support it is a simple matter to move the slide fasteners down to a desirable position in order to give the necessary release of pressure.

The invention also proposes to provide the brassière with shoulder straps and to provide straps connected with the top corners of the elastic insert and with the shoulder portions of the shoulder straps in order to support the elastic insert in the various partially open positions of the slide fasteners.

Furthermore, the invention proposes to so arrange the slide fasteners that they may be moved completely to the bottom of the elastic insert in order that the elastic insert is freed and may be completely removed. This is valuable for laundering the garment. The garment may also be worn in this condition.

Another object of the invention is the construction of a combination brassière slip as described which is simple and durable and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a back elevational view of a combination brassière slip embodying this invention.

Fig. 2 is a fragmentary enlarged detailed view of a portion of Fig. 1 illustrating particularly the

2

elastic insert, but in this figure the slide fasteners are shown partially open.

Fig. 3 is a fragmentary horizontal sectional view taken on the line 3—3 of Fig. 2.

Fig. 4 is a fragmentary vertical sectional view taken on the line 4—4 of Fig. 2.

Fig. 5 is a fragmentary elevational view of a portion of the garment showing particularly the details of one of the slide fasteners.

Fig. 6 is an elevational view of the elastic insert and its connecting straps completely removed from the garment.

The combination brassière slip, in accordance with this invention, includes a slip body section 10 having a brassière top portion 11 provided with an open back 12. An elastic insert 13 is provided for closing said open back. The brassière top portion 11 is also provided with the usual shoulder straps 15. The sides of the open back

12 and the sides of the elastic insert taper from the top to the bottom in order to provide a greater degree of resiliency along the top portion of the brassière top portion than along the bottom thereof.

Slide fasteners 16 connect the sides of the elastic insert 13 with the sides of the open back 12. These slide fasteners 16 are provided with control slides 17 having handles 18 provided with small prongs 19 engageable through openings 20 in the slides 17 for engaging the hooks 21 of the slide fastener stringers 26 for locking the slides in selective fixed positions along the hooks 21. These slide fasteners 16 are arranged so that the slides 17 thereof may be moved downwards to

30 various positions for freeing top portions of the elastic insert 13 in order to release resilient pressure of said brassière top portion about wearer's body. Straps 24 connect with the top corners of the elastic insert 13 and with the shoulder portions of the shoulder straps 15 in order to support the elastic insert 13 in open positions of said slide fasteners 16. The top ends of the straps 24 are provided with snap fasteners 25 engageable with complementary fastener elements

40 attached to the shoulder portions of the shoulder straps 15.

45 The slide fasteners 16 are of the construction which permits the complete removal of the elastic insert 13 when the slides 17 are moved to their bottom-most positions. In Fig. 6 the elastic insert 13 is shown completely removed from the garment.

Each slide fastener 16 includes adjacent stringers 26 provided with said hooks 21. One 50 line of the stringers 26 of each slide fastener is

attached along the inside edge portion of the elastic insert 13 and the other line is attached similarly along the inside edge portion of the open back, see particularly Fig. 3. A covering tape 27 is attached along one of the sides of the slide fastener for engaging across and covering the slide fasteners when the insert 13 is in position on the garment.

The operation and use of the combination brassière slip may be understood from the following:

In Fig. 1 the garment is illustrated with the elastic insert 13 in position and with the slide fastener 16 completely closed. In this position the brassière top portion 11 of the garment will be firmly about the body of a wearer. If it is desired to release some of the pressure of the brassière top portion 11 it is merely necessary to move the control slides 17 of the slide fasteners 16 downwards to selected positions, as for example the positions illustrated in Fig. 2. In these positions the slides 17 may be locked by merely moving the handles 18 thereof into down positions in the usual way. Now that the top portion of the insert 13 is not being stretched, the constricting action of the brassière top portion 11 of the garment will be reduced. The straps 24 serve to hold the top portion of the insert 13 in a raised position against bending and falling downwards. The insert 13 may be completely removed by moving the slides 17 to their bottommost positions.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new and desire to secure by United States Letters Patent is:

In a combination brassière slip, a slip body section having a brassière top portion provided with a back portion having an opening with slanting side edges, said opening extending from the top of said back portion downwards to about the

waist portion of said slip body section, an elastic insert with slanting side edges filling said opening, means for releasably connecting all portions of each of the sides of said insert with all portions of each of the sides of said opening in order that the complete insert or varying proportions of said insert from the top of said insert downwards may be released from the sides of said opening, shoulder straps for said brassière top portion extending from the top edge portion of the front of said brassière top portion to the top edge portion of the back of said brassière top portion at points adjacent the sides of said opening which is filled by said elastic insert, and short straps connecting at their bottom ends with the top corners of said elastic insert and at their top ends with portions of said shoulder straps which are located approximately midway between the ends of said shoulder straps in order to support the complete elastic insert or a varying proportion of the insert depending upon the distance the insert is detached from the top edge of the brassière top portion of said slip.

RAFAEL MARIN.
